UNITED STATES PATENT OFFICE.

LORIOT D. BOZORTH, OF BLACKWOOD, NEW JERSEY.

DESIGN FOR A TOY SCOOP-CART.

47,515.

Specification for Design.

Patented June 29, 1915.

Application filed November 17, 1914. Serial No. 872,668. Term of patent 7 years.

To all whom it may concern:

Be it known that I, LORIOT D. BOZORTH, a citizen of the United States, residing at Blackwood, in the county of Camden and State of New Jersey, have invented a new, original, and ornamental Design for Toy Scoop-Carts, of which the following is a specification, reference being had to the accompanying drawing, forming a part thereof.

Figure 1 is a view in side elevation of a toy scoop cart showing my new design. Fig. 2 is a top plan view, and Fig. 3 is a bottom plan view.

I claim:

The ornamental design for a toy scoop cart, as shown.

LORIOT D. BOZORTH.
